UNITED STATES PATENT OFFICE.

CHRISTOPHER J. THEUERNER, OF NEWARK, NEW JERSEY, ASSIGNOR TO HIMSELF AND C. FRED. CHURCH, OF SAME PLACE.

DESIGN FOR A RING.

SPECIFICATION forming part of Design No. 12,949, dated May 23, 1882.

Application filed April 11, 1882. Term of patent 7 years.

To all whom it may concern:

Be it known that I, CHRISTOPHER J. THEUERNER, of Newark, in the county of Essex and State of New Jersey, have invented a new and useful Improvement in Designs for Rings, of which the following is a specification.

My invention relates to an improvement in designs for rings; and it consists in the conformation substantially as hereinafter set forth.

10 Figure 1 is an edge view or elevation. Fig. 2 is a side elevation. Fig. 3 is a top view of the same. Fig. 4 is a top view, and Fig. 5 a side elevation, showing a modification.

First, my design consists in the corrugations 15 A on the outside of the box B for holding the stone or setting, and the ridges terminate with beads C on the top of the box when the ring is used for a raised setting, as in Figs. 4 and 5; but when the setting is flush with the top 20 of the box, as in Figs. 1, 2, and 3, the beads

are dispensed with and the top of the box is made smooth, and the flutes are only on the sides.

Second, the design is in the corrugations A on the part of the shank, D, which forms a connection with the box, while the lower part, E, is plain.

I claim—

1. The design for a ring herein shown and described, consisting of the shank having the part E plain and the part D corrugated, and the box corrugated.

2. The design for a ring herein shown and described, consisting of the box having the corrugations A, and beads C on the top of the box.

CHRISTOPHER J. THEUERNER.
